UNITED STATES PATENT OFFICE.

WILLIAM H. HART, OF NEW BRITAIN, CONNECTICUT.

DESIGN FOR A STRAP-HINGE.

SPECIFICATION forming part of Design No. 23,447, dated July 10, 1894.

Application filed April 11, 1894. Serial No. 507,180. Term of patent 14 years.

To all whom it may concern:

Be it known that I, WILLIAM H. HART, a citizen of the United States, residing at New Britain, in the county of Hartford and State 5 of Connecticut, have invented and produced a new and original Design for a Strap-Hinge, of which the following is a specification, reference being had to the accompanying drawing, forming part thereof, in which the figure 10 is a front view of a strap-hinge, showing my design.

Both of these leaves have the usual tapering form rounded at their outer ends and in the body portion toward the wider end I form

semi-circular notches 2 directly opposite each other, and from which notches the edges of the leaves are straight and gradually converge to their outer ends, as shown, thereby adding to the ornamental appearance of the leaves. These leaves are connected by the 15 ordinary knuckle portion 3, as shown.

What I claim is—

The design for a strap hinge, herein shown and described.

WM. H. HART.
